CLAIM

The ornamental design for installation tool for setting pull type fasteners, as shown and described.

DESCRIPTION

FIG. 1 is a perspective view of the installation tool with a nose assembly shown in phantom at the front end of the tool; FIG. 2 is front elevational view of the installation tool of FIG. 1;

FIG. 3 is a side elevational view of the installation tool of FIG. 1;

FIG. 4 is a rear elevational view of the installation tool of FIG. 1;

FIG. 5 is a top elevational view of the installation tool of FIG. 1 with the nose assembly shown rotated around 90° from that shown in FIGS. 1 and 3;

FIG. 6 is a bottom elevational view of the installation tool of FIG. 1 with the nose assembly shown rotated around 90° from that shown in FIGS. 1 and 3;

FIG. 7 is a perspective view of a second embodiment of FIGS. 1-6 with the nose assembly, which was shown in phantom, being shown in solid lines in the position depicted in FIGS. 1 and 3;

FIG. 8 is a top elevational view of the installation tool of FIG. 7 with the nose assembly shown in the position depicted in phantom in FIG. 5;

FIG. 9 is a bottom elevational view of the installation tool of FIG. 7 with the nose assembly shown in the position depicted in phantom in FIG. 6;

FIG. 10 is a front elevational view of the installation tool of FIG. 7;

FIG. 11 is a side elevational view of the installation tool of FIG. 7; and,

FIG. 12 is a rear elevational view of the installation tool of FIG. 7.
